UNITED STATES PATENT OFFICE

CHARLES C. HINE, OF NEWARK, NEW JERSEY.

DESIGN FOR TYPE.

Specification forming part of Design No. 5,982, dated July 16, 1872.

Specification describing a Design for the Alphabet, invented by CHARLES C. HINE, residing at Newark, New Jersey.

The nature of my design is fully represented in the accompanying drawing, to which reference is made.

Figure 1 represents the top work of each letter. Fig. 2 represents the bottom work of the same. Fig. 3 represents the central portion of the letters when made small. Fig. 4 represents the central portions of the letters when made large.

The central portions of the letters may be plain or fanciful. I prefer to make the cen-

tral parts of small letters plain black, as shown, and the central portions of large letters fanciful, as shown.

What I claim is—

The design for alphabet, substantially as shown.

In testimony that I claim the foregoing I have hereunto set my hand this 10th day of June, 1872.

C. C. HINE.

Witnesses:

EDWARD W. BELL,
R. H. LYON.
